ATTORNEY.

UNITED STATES PATENT OFFICE.

CHARLES V. MONSON, OF DULUTH, MINNESOTA.

HORSE-HITCHING DEVICE.

1,257,727.

Specification of Letters Patent. Patented Feb. 26, 1918.

Application filed October 11, 1917. Serial No. 195,934.

To all whom it may concern:

Be it known that I, CHARLES V. MONSON, a citizen of the United States, residing at Duluth, in the county of St. Louis and 5 State of Minnesota, have invented certain new and useful Improvements in Horse-Hitching Devices, of which the following is a specification, reference being had therein to the accompanying drawing.

10 This invention relates to safety devices for hitching horses to vehicles.

One object of the invention is to provide more simple and practical means than heretofore known, whereby, when properly adjusted, it becomes impossible for the horses hitched to a vehicle to move the latter except by the draft coming wholly upon their mouths.

20 Other characteristics and advantages of my novel combination of elements will appear in the further description of the device.

25 In the accompanying drawings forming part of this application and in which like reference characters indicate like parts:

Figure 1 is a top plan view of a fractured vehicle tongue equipped with my improved device,

Fig. 2 is a side elevation of a fragmental 30 portion of same,

Fig. 3 is a vertical sectional view on the line A—B, Fig. 1, showing the swing-tree as drawn from its normal position in relation to the evener, and

35 Fig. 4 is an enlarged front edge elevation of a fragmental portion of the evener.

1 represents the tongue or pole of a vehicle and which may be attached to the latter in any desired manner.

40 On the free end of the pole is carried the neck yoke 2 which is ordinarily attached by diagonal chains 3—3 leading from the extreme ends of the neck yoke to the free end of the pole and which is seen to permit of 45 considerable horizontal movement of the neck yoke longitudinally the tongue without becoming detached therefrom.

Other forms of neck yokes may be referred to as for example those having a ring 50 which slips on over the end of the tongue, but these also are susceptible of considerable movement longitudinally the tongue and will permit of the horses advancing accordingly without moving the vehicle provided they are not otherwise attached thereto.

34 represents the evener or doubletree to which the team of horses is attached by means of suitable swing-tree 4—4, there being one at each end of the evener, as is 60 the custom. The evener is here shown as carried upon the under side of the tongue and pivoted in the usual manner by the draw pin 5, there being a suitable hammer-strap 6 upon the under side of the evener 65 to form a substantial connection with the tongue.

The swing-tree 4—4 are yieldably attached to the ends of the evener in the following manner:

70 A metal plate 7 is scarfed into the front edge of each end of the evener and securely attached thereto by suitable through bolts 8 upon each plate and integral therewith is formed a forwardly extending guiding 75 head 18 having vertically opposed channels formed therein as at 9—9 and in which channels the slideable keeper 10 is engaged, the outer end of said keeper being bifurcated forming guides 11—11 which at all 80 times are engaged within the channels 9.

Upon the outer face of each guide 11 is formed a forwardly projecting lip 12, the outer extreme edges of which are turned inwardly and designed to overlap and hold the swing-tree attachment 13 when engaging same. The swing-tree attachment comprises a rectangular shaped base portion 14 having a forwardly extending loop 15 to which the swing-tree is attached and the 90 rearwardly rectangular shaped shank 16 which fits into a similarly shaped socket 17 formed in the head 18 when the swing-tree is held back against the evener.

85 A long contractile spiral spring 19 is attached at one end to the shank 16 of the swing-tree holder and passes in the opposite direction entirely through suitable holes 20 formed in the evener and on the back side thereof are attached to the extreme end 100 21 of suitable housings or supports 22 for said springs.

These supports I have shown as being composed of bent strips of slightly concavo-convex metal and longitudinally of which 105 the springs reciprocate.

It is evident that these may be made tubular and entirely surround the springs if preferred, and I have shown them as being arched inwardly toward the tongue to form 110 the least obstruction possible.

By this attachment of spring to the

swingle-tree, it becomes possible, when the keeper is withdrawn to non-engaging position, to withdraw the swingle-trees some considerable distance without causing draft 5 to any extent upon the vehicle.

For operating the keepers to and from engagement with the swingle tree connections, I provide a crank rod 23, through the evener 34, and to one side of the tongue, 10 said rod having a crank 24 upon its inner end for operating same and a vertically disposed cross arm lever 25 upon the opposite end to which the rods 26 and 27 are pivotally attached. The opposite end of the rod 27 is attached as at 28 to one of the 15 slideable keepers 10, and the opposite end of the rod 26 is attached as at 29 to the opposite slideable keeper 10.

Adjacent one of the slideable keepers 10, 20 I have illustrated a spring catch 30 fixed to the front edge of the evener and contacting the flat base portion of the keeper the latter having a V-shaped notch therein for engagement by the catch as at 31 to hold same in 25 its disengaged position, but which will slip out of the notch when the keeper is forced therefrom.

An elongated slot 32 is formed in the base portion of each keeper, through which a 30 guiding screw 33 extends to assist in further guiding and supporting the keeper and prevent its being cramped diagonally by the action of the operating rod.

Upon the tongue 1 and in any desired location convenient of access to the driver of the vehicle, which, in ordinary circumstances would be in close proximity to the evener, is mounted an upstanding line holding bracket or standard 35, which is preferably constructed of metal and having the upper extremity 36 thereof suitably shaped for the reception of rings 37 attached to the driving reins 38. These rings are so positioned longitudinally the reins that when 40 engaged upon the standard, the horses will be held in a normally backward position in relation to the vehicle, though not in any sense strained in such position.

In operation, the driver, when leaving the 50 vehicle, places the rein rings 37 over the hooked end 36 of the standard 35, as clearly shown in Fig. 2 of the drawings, then he will turn the crank 24 of the shaft 23 to a horizontal position, as shown in Fig. 1, 55 which will, by virtue of their connection to the cross-arm lever 25 on said crank shaft, withdraw the keepers 10 from active engagement with the swingle-tree holding means. This will permit of the swingle-tree 60 being drawn forwardly from the evener to the limit of the springs 19, without imparting any material draft upon the vehicle.

Thus it is seen that if the horses attempt to advance when the mechanism is thus adjusted, the reins will hold them and prevent 65

their leaving the vehicle or taking it with them, and by which means a practical safety horse hitching device is provided.

It is evident that various departures from the specific construction may be resorted to 70 without departing from the spirit of the invention.

Having thus described my invention, what I claim as new and desire to secure by Letters Patent, is:

75 1. In a device of the character described, the combination with a vehicle having means for attachment of a team of horses thereto comprising a tongue, evener, swingle-trees and neck yoke, of means for changing the normal unyieldable attachment of the swingle-trees to the evener to a yieldable attachment, said means including an operating element manually engageable at the rear of the evener for unlocking the swingle-trees 85 and held in its locked position by gravity and fixed means upon the tongue adjacent the evener for temporarily holding the horses' reins whereby any movement ahead on the part of the horses will cause all of 90 the resultant draft to come upon the reins.

2. In a device of the character described, the combination with a vehicle having means for attaching a team of horses thereto comprising a tongue, evener, swingle-trees and 95 neck yoke, of means for changing the normal unyieldable attachment of the swingle-trees to the evener to a yieldable attachment, said means including an operating element extending horizontally through the evener 10 and engageable at the rear thereof for locking and unlocking the swingle-trees and fixed means upon the tongue adjacent the evener for temporarily holding the horses' reins whereby any movement ahead on the 10 part of the horses will cause all of the resultant draft to come upon the reins.

3. In a device of the character described, the combination with a vehicle having means for attaching a team of horses thereto 11 comprising a tongue, an evener, swingle-trees and neck yoke; of a contractile spiral spring attaching each swingle-tree to the evener and passing therethrough, an inwardly curved rearwardly extending support for each spring rigidly fixed to the rear side of the evener, manually controlled means for unyieldably uniting the swingle-trees with the evener and means for securely holding the reins to the vehicle.

4. In a device of the character described, the combination with a vehicle having means for attaching a team of horses thereto comprising a tongue, an evener, swingle-trees and neck yoke; of a contractile spring attaching each swingle-tree to the evener and passing therethrough, an inwardly curved rearwardly extending support for each spring rigidly fixed to the rear side of the evener, a socket about each spring and upon 11

the forward side of the evener, a shank attached to each swingle-tree and normally engaged within its respective socket, a slideable member adjacent each swingle-tree connection with the evener for overlapping engagement with the shank, means for manually manipulating the slideable members and means within convenient reach of the driver

for holding the horses' reins against movement by the horses.

In testimony whereof I hereunto affix my signature in the presence of two witnesses.

CHARLES V. MONSON.
